TRACTOR ATTACHMENT FOR CABLE OR
HYDRAULIC TIPPLE LOADERS

Melvon L. Vincent, Alberhill, Calif.

Application January 3, 1951, Serial No. 204,227

4 Claims. (Cl. 214—707)

1

This invention relates to a material moving machine, and more particularly to a power operated bucket or carrier for such a machine.

The object of the invention is to provide a power operated bucket for attachment to a conventional machine, such as a tractor, whereby large quantities of material such as coal or dirt can be handled, moved, or loaded onto a vehicle.

Another object of the invention is to provide a material lifting bucket for a machine wherein the bucket will gradually be tilted as it is raised so that by the time the bucket reaches its uppermost position the bucket will be in dumping position so that the material will be dumped into a waiting vehicle or the like.

A further object of the invention is to provide a tractor mounting means which is extremely simple and inexpensive to manufacture.

Other objects and advantages will be apparent during the course of the following description.

In the accompanying drawings, forming a part of this application, and in which like numerals are used to designate like parts throughout the same.

Figure 1 is a side elevational view of the power operated bucket of the present invention, the bucket being attached to a conventional tractor (broken lines).

Figure 2 is a front elevational view of the assembly of Figure 1.

Figure 3 is a sectional view taken on the line 3—3 of Figure 2.

Figure 4 is a sectional view taken on the line 4—4 of Figure 2.

Figure 5 is an enlarged sectional view taken on the line 5—5 of Figure 1.

Figure 6 is a front elevational view of a modified bucket assembly.

Figure 7 is a vertical sectional view taken through the assembly of Figure 6.

Figure 8 is a sectional view taken on the line 8—8 of Figure 6.

Referring in detail to Figures 1 through 5 of the drawings, the numeral 20 designates one of a pair of horizontally disposed arms which may be made of any suitable material such as steel. The arms 20 are adapted to be connected to a conventional tractor which is indicated by the letter T, the tractor being shown in broken lines, Figures 1 and 2. The rear ends of the arms 20 are adapted to be connected to a horizontally disposed shaft 31 which extends beneath the tractor T, and the means for connecting the arms to the shaft 31 is indicated by the numeral 32. The mounting means 32 includes a bracket 33

2

which is secured as by welding to the rear end of the arm 20, and a plate 34 is arranged on the opposite side of the shaft 31 and is connected to the bracket 33 by suitable securing elements such as bolt and nut assemblies 35.

The mounting means of the present invention further includes an inclined brace 36 which is arranged on each side of the tractor T, the lower ends of the braces 36 being secured as by welding to the arms 20. Connected to the upper end of each of the braces 36, and also connected to the front end of each of the arms 20 is a set of tracks which are indicated by the numeral 37. Thus, it will be seen from Figures 2 and 4 that a set of the tracks 37 are arranged on each side of the tractor T at the front thereof.

Each of the tracks 37 comprises a first or inner U-shaped trackway 38, and the U-shaped track 38 opens inwardly toward the tractor T. Each set of tracks 37 further includes a second or outer track 39 which also has a U-shape, and the track 39 opens outwardly away from the tractor T, Figure 4. As best seen in Figures 1 and 3, the tracks 38 and 39 include curved portions, so that the movable bucket 40 will be in dumping position by the time it reaches the upper ends of the tracks.

The bucket 40 includes a back wall 41, and extending rearwardly from the back wall 41 is a pair of spaced parallel vertically disposed ears 42. A pin 44 rotatably connects a roller 43 to each of the ears 42, and the rollers 43 travel or ride in the inner tracks 38. Also extending rearwardly from the back wall 41 is a pair of spaced parallel vertically disposed flanges 45, and a pin 46 rotatably connects a roller 47 to each of the flanges 45. The rollers 47 ride in or travel in the tracks 39. Thus, it will be seen that as the bucket 40 is elevated or raised, the rollers 47 and 43 will travel in the tracks 39 and 38 so that the bucket 40 will be moved from the solid line position shown in Figure 1 to the broken line position shown in Figure 1 whereby the bucket 40 will be in dumping position by the time it reaches its uppermost position.

The bucket 40 further includes a bottom wall 48, and extending forwardly from the front edge of the bottom wall 48 is a plurality of spaced parallel teeth 49. The teeth 49 facilitate the breaking-up of dirt, or other material which is to be picked-up by the bucket 40. A roller 43 is rotatably connected to a pair of spaced parallel arms 50 by a pin 51, the arms 50 being secured to the flange 45 as by welding. The roller 43 also

rides in the outer track 39, and the roller 48 helps keep the parts in alignment.

A means is provided for raising and lowering the bucket 40, and this means comprises a horizontally disposed bar 51 which extends between the pair of flanges 45 and is secured thereto. Connected to the bar 51 is a pair of sheaves or pulleys 52, while extending between the upper ends of the tracks 38 and secured thereto, is a U-shaped channel member 53, Figure 1. A pair of pulleys 54 are rotatably connected to the stationary channel member 53, and a cable 55 is trained over the pair of pulleys 54, the cable 55 adapted to be connected to the power take-off mechanism on the tractor T. The cable 55 is also trained over the pair of sheaves 52 which are connected to the bar 51, and the free end of the cable 55 is connected to an anchor hitch 56, Figure 2. Thus, upon actuation of the power take-off mechanism on the tractor T, the cable 55 will cause the bucket 40 to be elevated, and as the bucket 40 is elevated, the rollers 43 and 47 will follow or travel the path of the tracks 38 and 39 so that the bucket 40 will move from the solid line position of Figure 1 to the broken line position whereby the material in the bucket will be dumped gradually as the bucket is elevated.

A horizontally disposed beam 57 extends between the front ends of the arms 23 and is secured thereto, Figure 3, and a pair of caster wheels 58 are dependently supported or connected to the beam 57.

Referring to Figures 6, 7 and 8 there is shown a modified assembly for attachment to the tractor T, and in Figures 6, 7 and 8 the loading bucket is again indicated by the numeral 40, the loading bucket 40 including the back wall 41, bottom wall 48 and teeth (not shown). Extending rearwardly from the back wall 41 are the ears 42 and flanges 45. Rollers 43 and 47 are connected to these members, and the rollers 43 are adapted to travel in the tracks 38, while the rollers 47 are adapted to travel in the tracks 39, as previously described. Thus, by the time the bucket 40 reaches its uppermost position, it will have dumped gradually the material that was being lifted.

Extending between the pair of tracks 38 and secured thereto as by welding is a horizontally disposed angle member 61, Figures 6 and 7. A pair of vertically disposed spaced parallel hydraulic cylinders 59 have their lower ends secured to the beam 57, and a piston rod 60 is slidably or reciprocally arranged in each of the cylinders 59. A hose 62 serves to connect each of the cylinders 59 to a suitable source of hydraulic fluid, and a sprocket 63 is rotatably connected to the upper end of each of the rods 60. A chain 64 is trained over each of the sprockets 63, and one end of each of the chains 64 is connected to the bar 51. The other ends of the chains 64 are connected to lugs 65 which are secured to the channel member 61. Thus, when hydraulic fluid is supplied to the cylinders 59, the rods 60 will be raised out of the cylinders 59 to thereby raise or elevate the bucket 40.

A horizontally disposed brace 65 extends between the upper ends of the tracks 38 and is secured thereto in order to help maintain the tracks in their proper spaced relation, and extending upwardly from the channel member 61 is a pair of spaced parallel vertically disposed tracks 66. Suitable braces 67 extend between the tracks 66 and 38, and a spaced member 68 is movably arranged in the tracks 66. The spacer member 68 is connected to the sprocket 63 by links 69. A

pair of brackets 70 are connected to the channel member 61 by suitable securing elements such as bolt and nut assemblies 71, and the brackets 70 serve to connect the upper ends of the cylinders 59 to the channel member 61.

From the foregoing, it is apparent that a bucket mounting means has been provided for attachment to a tractor whereby the loaded bucket of dirt, coal, or other material will be moved to dumping position by the time it reaches the top of the tracks. Thus, as shown in Figures 1 through 5, upon actuation of the cable 55 which is connected to the power take-off mechanism on the tractor, the bucket 40 will be raised and gradually tilted as shown in the three positions in Figure 1. This tilting is caused by the rollers 43 and 47 which ride in the tracks 38 and 39, the curvature of these tracks causing the bucket to move into dumping position.

In Figures 6, 7 and 8 there is shown a modified form of the invention wherein the elevation or raising of the bucket 40 is accomplished by actuation of the hydraulic cylinders 59. Thus, upon supplying hydraulic fluid through the hoses 62, the rods 60 will be moved upwardly in the cylinders 59 whereby the chains 64 will raise the bucket 40 and as the bucket 40 moves upward the rollers 43 and 47 will ride in the tracks 38 and 39 to cause the bucket 40 to tilt and gradually be dumped.

Having described the invention, what is claimed as new is:

1. In a tractor mounting means, a horizontally disposed arm adapted to be connected to each side of a tractor, an inclined brace extending upwardly from each of said arms and secured thereto, a first and second vertically disposed track arranged on each side of the tractor and secured to said braces and to said arms, each of said first tracks opening toward the tractor and each of said second tracks opening away from the tractor, a bucket movably connected to said tracks, said bucket including a bottom wall and a back wall, a pair of spaced parallel vertically disposed ears projecting rearwardly from said back wall and secured thereto, a roller connected to each of said ears and riding in said first track, a flange projecting rearwardly from each end of said back wall, a roller connected to each of said flanges and riding in said second track, said second tracks and first tracks being shaped so that the bucket gradually moves into dumping position as it is raised, caster wheels, and means for raising and lowering said bucket, said means comprising a horizontally disposed bar extending between said flanges and secured thereto, a pair of sheaves connected to said bar, a channel member extending between the upper ends of said first tracks and secured thereto, a pair of pulleys supported on said channel member, and a cable trained over said pulleys and over said sheaves and adapted to be connected to a power take-off mechanism on the tractor.

2. In a tractor mounting means, a horizontally disposed arm adapted to be connected to each side of a tractor, an inclined brace extending upwardly from each of said arms and secured thereto, a first and second vertically disposed track arranged on each side of the tractor and secured to said braces and to said arms, each of said first tracks opening toward the tractor and each of said second tracks opening away from the tractor, a bucket movably connected to said tracks, said bucket including a bottom wall and a back wall, a pair of spaced parallel vertically disposed ears

projecting rearwardly from said back wall and secured thereto, a roller connected to each of said ears and riding in said first track, a flange projecting rearwardly from each end of said back wall, a roller connected to each of said flanges and riding in said second track, said second tracks and first tracks being shaped so that the bucket gradually moves into dumping position as it is raised, caster wheels, and means for raising and lowering said bucket, said means comprising a beam extending between the lower ends of said first tracks and secured thereto, a pair of vertically disposed hydraulic cylinders having their lower ends secured to said beam and adapted to be connected to a source of hydraulic fluid, a piston reciprocably arranged in each of said cylinders, a horizontally disposed angle member extending between said first tracks and secured thereto, a horizontally disposed bar extending between said flanges and secured thereto, a sprocket rotatably mounted on the upper end of each of said pistons, a chain trained over each of said sprockets and having one end connected to said channel member and its other end connected to said bar.

3. A tractor mounting means comprising a horizontally disposed arm adapted to extend along each side of a tractor, a horizontally disposed shaft extending beneath said tractor, a bracket secured to the rear end of each of said arms, a plate arranged on the opposite side of said shaft from said bracket and secured to said bracket, an inclined brace extending upwardly from each of said arms and secured thereto, a first and second vertically disposed track arranged on each side of the tractor and secured to said braces and to said arms, each of said first tracks opening toward the tractor and each of said second tracks opening away from the tractor, a bucket movably connected to said tracks, said bucket including a bottom wall and a back wall, a plurality of spaced parallel teeth extending from said bottom wall, a pair of spaced parallel vertically disposed ears projecting rearwardly from said back wall and secured thereto, a roller connected to each of said ears and riding in said first track, a flange projecting rearwardly from each end of said back wall, a roller connected to each of said flanges and riding in said second track, said second tracks and first tracks being shaped so that the bucket gradually moves into dumping position as it is raised, a horizontally disposed beam extending between the front ends of said arms and secured thereto, a plurality of caster wheels carried by said beam, and means

5 for raising and lowering said bucket, said means comprising a horizontally disposed bar extending between said flanges and secured thereto, a pair of sheaves connected to said bar, a channel member extending between the upper ends of said first tracks and secured thereto, a pair of pulleys supported on said channel member, and a cable trained over said pulleys and over said sheaves and adapted to have one end connected to a power take-off mechanism on the tractor and its other end connected to said channel member.

4. In a tractor mounting means, an arm adapted to be connected to each side of a tractor, an inclined brace extending upwardly from each of said arms and secured thereto, a first and second track arranged on each side of the tractor and secured to said braces and to said arms, each of said first tracks opening toward the tractor and each of said second tracks opening away from the tractor, a bucket movably connected to said tracks, said bucket including a bottom wall and a back wall, a pair of ears projecting rearwardly from said back wall and secured thereto, a roller connected to each of said ears and riding in said first track, a flange projecting rearwardly from each end of said back wall, a roller connected to each of said flanges and riding in said second track, said second tracks and first tracks being shaped so that the bucket gradually moves into dumping position as it is raised, caster wheels, and means for raising and lowering said bucket, said means comprising a bar extending between said flanges and secured thereto, a pair of sheaves connected to said bar, a channel member extending between the upper ends of said first tracks and secured thereto, pulleys supported on said channel member, and a cable trained over said pulleys and over said sheaves and adapted to be connected to a power take-off mechanism on the tractor.

MELVON L. VINCENT.
